COMBINATION MORTAR

Cleve F. Shaffer, San Francisco, Calif., assignor of thirty per cent to Martin C. Mogensen, Martinez, thirty per cent to Herbert W. Erskine, Piedmont, five per cent to Herman J. Fanger, Oakland, and five per cent to Henry Gruenhagen, Oakland, Calif.

Application August 11, 1941, Serial No. 406,301

5 Claims.

(Cl. 89—1)

This invention relates to mortars of the military type and more particularly to a combination mortar for firing either by trigger operation or so-called "drop-firing," and for selective use as a shoulder weapon or for ground firing. It is particularly adapted for use with a type of grenade disclosed in my co-pending application Serial No. 392,878, filed May 10, 1941, (Patent No. 2,378,735, granted June 19, 1945) for Grenade. By reference to my co-pending application for grenade, it will be noted that there was disclosed therein a grenade comprising an explosive head and a shank or shaft attached thereto. Broadly, that is the structure of one type of hand grenade employed by military forces at the present time. In that grenade I disclosed an adapter unit whereby the grenade might be employed for manual throwing or for firing in a mortar of the type disclosed herein. The present invention incorporates the features of the mortar for firing a grenade and this application is a continuation in part of my said co-pending application referred to above, and in which the advantages of a light-weight combination mortar for firing such grenades was set forth.

Among the objects of the present invention are to provide a simple, compact and light-weight military mortar adapted for transportation and fast set-up, and operation in its entirety by one man, and including particularly parachute and air-borne troops. A further object of the invention is to provide a mortar adaptable for use in trigger and so-called drop-firing from the ground, or for use as a shoulder weapon with a minimum recoil for conditions of terrain, such as flooded areas, swamps, sand, etc., where an ordinary mortar cannot be laid; and for conditions where grenade throwing would be impossible by reason of distance, or directive accuracy, or other reasons; a further object is to provide a weapon suitable for the smallest group of soldiers, or squad, which does not require special ammunition, the supply of which might be cut off, but which can use the same grenade as is provided the individual soldier. A further object is to provide a mortar having a controlled exhaust from the combustion chamber whereby the recoil of the mortar may be controlled when fired and also whereby the distance flight-range of the grenade or projectile may likewise be controlled.

With the foregoing and other objects in view, all of which will be more apparent as this description proceeds, the invention is exemplified in one form in the novel construction and combination of parts hereinafter described, illus-

trated in the accompanying drawing, and pointed out in the claims hereto appended, it being understood that various changes in the form, proportion, size and details of construction of the apparatus may be resorted to within the scope of the appended claims without departing from the spirit or sacrificing any of the advantages of the invention.

To more clearly comprehend the invention, reference is directed to the accompanying drawing wherein:

Fig. 1 is a perspective view of the mortar of the invention mounted upon a base plate.

Fig. 2 is a side elevation partly broken away of the mortar of the invention mounted in shoulder-firing relation to a combined casing and shoulder stock.

Fig. 3 is a fragmentary longitudinal view of the mortar barrel partly in section and partly broken away.

Fig. 4 is an enlarged side elevation of a calibrated dial structure and showing a valve controlling member fragmentarily.

Fig. 5 is a perspective of carrying case housing the mortar barrel therein, in the manner of carrying the mortar in the case by shoulder strap.

Fig. 6 is a side view of a spade member including in section a fragmentary portion of a base plate.

Fig. 7 is a perspective view of a keyed bracket member.

Fig. 8 is a transverse cross section of carrier case on line VIII—VIII of Fig. 2.

Referring to the drawing, in which like characters of reference designate corresponding parts in the several views, there is provided a mortar barrel 10 which is tubular, as best shown in Fig. 3, and which is preferably threaded at its discharge or muzzle end as at 11 and is closed at its opposite end by a breech block generally indicated at 12. The barrel 10 may be reinforced circumferentially at the breech end by a sleeve 13 which may be shrunk into tight engagement with the exterior of the barrel as at 14 providing an end portion of the barrel with extra thickness which may have threads 15 whereby the breech block 12 and the barrel may be relatively tightly connected.

The breech block 12 is a relatively solid heavily built member so as to take the rearward thrust of the explosive force in the barrel, but a portion thereof is recessed to receive mechanism for a firing pin 16 which is normally maintained at a forward position as shown in Fig. 3 by coil spring 17 which is relatively stiff. The firing pin may

be retracted and released for percussion firing by an exterior trigger member 18 which has a cam 19 internally of the breech block and which engages a small plate 20 on the firing pin 16 to compress the spring 17 rearwardly, the cam having a flat side which in the course of rotation of the trigger 18 releases the plate 20 so that the firing pin is forcefully actuated forwardly to contact a fuse cap of a shell 21 within the barrel. The breech block is also provided with a conduit 22 which communicates with the explosion chamber of the barrel 10 and with a recess 23, the latter also having in communication therewith an exhaust tube 24 which extends longitudinally of the exterior of the mortar barrel 10 and has a free open end 25 adjacent the mortar muzzle which is stabilized thereat by a split ring member 26, the top 26^a of which is an aiming sight. The communication between the conduit 22 and the exhaust tube 24, through recess 23, is adjustably controlled by a valve stem 27 which is threadedly mounted in the recess 23 and is manipulable by a thumbnut 28, the latter having a pointer 29 which is turnable with the thumbnut 28 to different positions on the two superposed calibrated dials 30 and 31, each having separate calibrations thereon to indicate the extent to which the valve stem 27 should be opened or closed to secure desired range of projectile, or to control recoil, dependent on whether the mortar is being employed as a ground firing weapon as shown in Fig. 1 or as a shoulder firing weapon as shown in Fig. 2. Obviously, the more the valve stem 27 is opened the greater the communication between the conduit 22 and the exhaust tube 24, for controlling the amount of explosive gases which are exhausted through the conduit and exhaust tube for reducing the explosive force exerted upon the projectile in the barrel. It is also obvious that, though the explosive gases exhausted through the conduit and tube 22, 24 will decrease the projected flight of a projectile, it also regulates to adjustably increase or decrease the amount of recoil in the mortar when employed as a shoulder weapon.

Rearwardly of the breech block and closing the rearward end of the bore therein as by threads 33 is a member which for lack of a better term is called a bastion block 34 to distinguish it from a buttress block hereinafter mentioned. Besides serving as a closure for the breech block and as a rear end mounting for the trigger pin 16, the bastion block serves as a foot by which the mortar may be mounted on a base member 35 for ground firing as shown in Fig. 1, for which purpose the bastion block is provided in its butt with a threaded recess 36. To each side thereof is mounted a tubular lug 37 which receives therethrough pintle pins 38 by which the bastion block is hingedly connected to correspondingly bored straps 39 fixedly attached to the base 35. In the present exemplification the base member 35 comprises segmental plates 35^a ad 35^b each of which is hinged by a pintle 38 to one side of the bastion block so that the segments of the plates may be hingedly folded up to lie flat against the sides of the mortar barrel, one of the plates having a recess 40 in its circumferential edge to accommodate the finger grip portion of the trigger 18 when the plates are thus folded. A spirit level device 41 may also be mounted on the bastion block to visibly indicate whether the mortar base is horizontal to the ground so that the barrel of the mortar which is in fixed relation to the base is at its fixed or predetermined elevation

and thus is at proper firing angle in ground firing. A means are provided for stabilizing the firing of the mortar in ground firing as herein shown comprising a spade spike 42 for entry into the ground, the spade having at its upper end a plate 43 which is circumferentially threaded as at 44 and has an axially extended threaded stem 45 for passing through an opening 46 in the base member 35 and threadedly engaging the recess 36 in the bastion block; the plate 43 when pressed against segmental plates 35^a, 35^b holds them rigid in proper relationship with horizontal spirit level 41, the purpose of threading the circumference of plate 43 being to permit the spade spike to form a barrel closure when not in use, to be carried in the muzzle end of the barrel by engagement of the threads 44 with the barrel threads 11, thus keeping dirt, etc., out of the barrel.

A hand grip member 46 may also be attached exteriorly of the barrel 10 by means of split rings 47, being spaced from the barrel as shown in Fig. 3 and having perforations 48 therein to prevent it from becoming overheated.

A casing 50 is provided to hold the mortar when it is being transported as by shoulder strap 51 in the manner shown in Fig. 5. This casing is tubular and has an offset tubular portion 50^a so that the exhaust tube 24 will readily slide into the casing with the barrel. When the mortar is within the barrel the threaded stem 45 may extend through a small opening 51^a and thus serve to center the barrel in the casing. It is preferred that the casing be somewhat shorter than the barrel 10 so that the mechanism in the breech block end will project somewhat beyond the casing, but at the same time be protected by the folded plates 35^a and 35^b.

When desired, the casing may serve as a shoulder stock so that the mortar may be adapted for shoulder firing. For this purpose, there is mounted at the open insert end portion of the casing a shoulder butt 52 which at one end has hinged connection 53 to a bracket 54 which is in turn secured to the open end portion of the casing.

At its opposite end, the shoulder butt 52 is provided with a thumb-released spring hook 55 which engages a latch as at 56 on the casing and thus holds the shoulder butt 52 in close and rigid contact with the open end of the casing and thereby completes a shoulder stock in like manner to the stock of a rifle.

From Fig. 5, it will be observed that when the mortar is mounted within the casing, the butt 52 is swung outward on its hinge 53 whereupon the spring hook 55 engages a notch 57 in the bottom of the bastion block and thus serves to hold the mortar within the casing, and also serves to protect the breech-end mechanism on the side thereof which contains the level 41 and the calibrated dials 30, 31 and the thumb-nut valve regulator 28. The hinge 53 has two clamp nuts 58 which carry thereunder spring fingers 59 which engage the outer surface of the plates 35^a, 35^b to maintain them in position when the plates are folded against the barrel.

When employing the mortar as a shoulder weapon, the pintle pins 38 are withdrawn from engagement with the plates 35^a, 35^b, and the butt end of the bastion block may then be similarly mounted by the same pins in a buttress block 60 mounted on the outside of the casing 50 intermediate its ends, the buttress block having flanges 61 having suitable holes therethrough for reception of the pintle pins 38 which likewise pass through the tubular lugs 37 of the

bastion block 34. The closed end of the casing which is opposite the shoulder butt has an angle-iron bracket 62 fixedly secured thereto and providing a slot 63 in one of its arms which lays parallel and preferably in close contact with the outer surface of the casing 50, the slot 63 having a key slot 64 therein to receive the complementarily keyed lug 65 which is mounted on the mortar barrel. Thus, the mortar barrel is securely and quickly fastened to and stabilized against either horizontal or vertical movement relative to the casing 50 and the combined barrel and casing become a shoulder weapon for operation by means of the trigger 18.

Other facilities may be optionally provided in connection with the use of the mortar as a shoulder weapon, one of which may be a spring claw 67 which is pivotally mounted as at 68 on a half collar 69 which is optionally rotatable around outer periphery of the mortar barrel by adjustment of nut on bolt 69^a of tightening strap 69^b, the claw 67 having an extending finger 70 for engaging a lug 71 on half collar 69. Thus, the claw 67 may normally be folded up to lie against the barrel as shown in dotted lines in Fig. 2, but when desired may be turned outwardly until the finger 70 engages the lug 71 and the claw is then adaptable for engaging a fence post or window sill downwardly, as shown in Fig. 2, or by rotating the collar 90 degrees so that pivot 68 is beneath the barrel, the claw may be extended horizontally outward as shown in Fig. 1 to engage a tree, the side of a building, pole, or other substantially solid body for stabilization of the mortar in aiming and absorbing recoil when it is used as a shoulder weapon.

It has briefly been stated that the present mortar is especially adapted for firing the grenade described in my previously filed co-pending application. As shown in Fig. 3 hereof the grenade is provided at one end with an adapter which comprises an elongated tubular member generally indicated 75 which is perforated as at 76 and has axially longitudinal fins 77 about its exterior so that the tubular member fits slidably within the barrel 10 to receive the explosive shell 21 which is fired by the firing pin 16. It will be understood that the shaft of the grenade of which the adapter 75 constitutes one end portion, extends the entire length of the barrel 10 and has its explosive head 78 preferably extending beyond the muzzle end of the barrel. No further description of the grenade is deemed necessary in view of its very complete description in my aforesaid co-pending application. However, it is to be understood that this mortar may use a shorter grenade, with head of smaller dimensions, inside the barrel, and is not restricted to any type of grenade.

When used as a shoulder weapon, the spike or spade can be put inside the case to prevent loss and the base plates put into breast pockets of a soldier as shields, and of course, the pins can be chained to the mortar base so that no parts will be lost. Preferably all screws, bolts, etc., have a slot so that a coin can turn them.

From the foregoing description, it will be noted that I have provided a mortar with all parts attached and assembled for fast set-up and laying which can be made of very light construction, which can be conveniently transported and operated by one man, is especially adaptable, in combination with its casing, for use by all categories of troops who will always have a potential supply of its ammunition, and which may be employed

as a ground weapon as shown in Fig. 1, in which event it may be utilized for either drop firing or trigger firing; and is also adapted in combination with a utilization of the casing as a shoulder weapon.

In other words, I have provided a weapon that greatly increases the individual soldier's field and range of action, fire power and importance, and gives to the army using it a vital advantage in front line, direct and indirect, light artillery against enemy personnel.

Having thus described my invention, I claim:

1. A military mortar including a barrel having a muzzle end for receiving an explosive projectile, and having its opposite end closed by a breech block, and having a firing pin in the breech block and a trigger for operating the firing pin, in combination with a casing adapted selectively to receive the mortar barrel therein and as a shoulder stock, said casing having an exterior buttress block intermediate its ends adapted for receiving thereagainst the bastion block of the mortar barrel, and a shoulder butt hingedly connected to the casing at an end portion, the said shoulder butt having a spring hook member adapted for lockingly engaging the bastion block when the mortar is within the casing and for lockingly engaging the casing body when the mortar is mounted on the exterior of the casing, the barrel of the mortar including adjacent its muzzle end a claw member for engaging an extraneous object for stabilizing the mortar barrel and absorbing recoil when the mortar is employed as a shoulder weapon.
2. A military mortar including a barrel having a muzzle end for receiving an explosive projectile, and having its opposite end closed by a breech block, and having a trigger operated firing pin in combination with a casing adapted selectively to receive the mortar barrel therein and as a shoulder stock, said casing having an exterior buttress block intermediate its ends adapted for receiving thereagainst the bastion block of the mortar barrel, means for releasably connecting the mortar barrel to the exterior of the casing and holding the bastion block and buttress block in abutting relation, and a shoulder butt hingedly connected to the casing at an end portion, the said shoulder butt having a spring hook member adapted for lockingly engaging the bastion block when the mortar is within the casing and for lockingly engaging the casing body when the mortar is mounted on the exterior of the casing, the barrel of the mortar including adjacent its muzzle end a claw member for engaging an extraneous object for stabilizing the mortar barrel and absorbing recoil when the mortar is employed as a shoulder weapon.
3. A military mortar including a barrel having a muzzle end for receiving an explosive projectile, and having its opposite end closed by a breech block, and having a firing pin in the breech block and a trigger for operating the firing pin, in combination with a casing adapted selectively to receive the mortar barrel therein and as a shoulder stock, said casing having an exterior buttress block intermediate its ends adapted for receiving thereagainst the bastion block of the mortar barrel, and a shoulder butt hingedly connected to the casing at an end portion, the said shoulder butt having a spring hook member adapted for lockingly engaging the bastion block when the mortar is within the casing and for lockingly engaging the casing body when the mortar is mounted on the exterior of the casing.

4. A military mortar including a barrel having a muzzle end for receiving an explosive projectile, and having its opposite end closed by a breech block, and having a trigger operated firing pin in combination with a casing adapted selectively to receive the mortar barrel therein and as a shoulder stock, said casing having an exterior buttress block intermediate its ends adapted for receiving thereagainst the bastion block of the mortar barrel, means for releasably connecting the mortar barrel to the exterior of the casing and holding the bastion block and buttress block in abutting relation, and a shoulder butt hingedly connected to the casing at an end portion, the said shoulder butt having a spring hook member adapted for lockingly engaging the bastion block when the mortar is within the casing and for lockingly engaging the casing body when the mortar is mounted on the exterior of the casing.

5. A mortar comprising a unitary assembly of a barrel having a muzzle end for receiving an

explosive projectile and being closed at its opposite end by a breech block having a firing pin and a trigger for operating the firing pin, in combination with a hollow casing having internal dimensions sufficient for receiving and enclosing the unitary barrel assembly, said casing having at one end a closure member adapted, selectively, as a shoulder butt and as a releasable closure member for said casing end, and said casing and said barrel assembly each having on the exterior thereof a plurality of relatively spaced releasable locking connecting means adapted for interengagement to releasably connect the barrel assembly and casing, one of said locking means being spaced intermediate the ends of the respective barrel and casing, whereby, when said plurality of locking means of casing and barrel are interengaged, an end portion of the barrel and an end portion of the casing overlap each other in locked engagement.

CLEVE F. SHAFFER.
